(57) CLAIM

The ornamental design for a beauty salon chair with curved armrests, as shown and described.

DESCRIPTION

FIG. 1 is a perspective view of a beauty salon chair with curved armrests showing my new design;

FIG. 2 is a top plan view of the beauty salon chair with curved armrests of FIG. 1;

FIG. 3 is a front elevational view of the beauty salon chair with curved armrests of FIG. 1;

FIG. 4 is a left side elevational view of the beauty salon chair with curved armrests of FIG. 1, the opposite side being identical;

FIG. 5 is a back elevational view of the beauty salon chair with curved armrests of FIG. 1; and,

FIG. 6 is a bottom plan view of the beauty salon chair with curved armrests of FIG. 1.

The broken line showing the leg support in FIG. 1 is for illustrative purposes only and forms no part of the claimed design.
